LAPPING APPARATUS

David A. Wallace, Detroit, Mich., assignor to
 Chrysler Corporation, Highland Park, Mich., a
 corporation of Delaware

Application March 24, 1937, Serial No. 132,688

9 Claims. (Cl. 51—117)

This invention relates to improved lapping apparatus.

More particularly, the invention pertains to lapping of surfaces of apparatus and parts thereof which operate in rubbing, sliding or rotative bearing-like, or frictional contact with other parts.

One of the main objects of the invention is to provide between an article being lapped and a lapping element, a relative movement which is a resultant of a plurality of different simultaneous component movements of the lapping element and the work respectively.

Another object of the invention is to produce relative movement of this character between a lapping element and a surface being lapped which is the resultant of so many components that even during repeated application of the lapping element to the work surface, no isolated area or particle of the lapping element will be repeatedly applied to the same increment of area of the work.

A still further object of the invention is to provide relative movement between a lapping element and a piece of work which is a resultant of simultaneous relative rotating and revolving actions between the work and the lapping element.

Other objects of the invention are to provide in lapping apparatus of this character, means for rotating a lapping element about one axis and revolving the same about another axis during application of the element to a surface of a piece of work; to provide a work support by which a piece of work is rotated about one axis and revolved about another axis during application thereto of a simultaneously rotating and revolving lapping element; and to provide a lapping tool for operating upon work supported by, and moving in accordance with the movements of a work support of the foregoing character, which simultaneously rotates and reciprocates the lapping element while the latter is contacted with the work.

Additional objects of the invention are to provide means in lapping apparatus of this character for simultaneously rotating about one axis and revolving about another axis, a pair of opposed lapping elements while the latter are in lapping engagement with opposite portions of a plurality of pieces of work; to provide a member for holding the pieces of work in a fixed spaced relationship between the opposed lapping elements during operation thereof and which also accommodates rotation of the pieces of work

about certain axes thereof; and to provide means for drivingly operating the opposed lapping element in respectively opposite directions so as to promote uniform turning of the pieces of work about their respective axes.

Another object of the invention is to provide an improved lapping member having un-uniformly shaped lapping surfaces yieldably mounted in a substantially common plane and asymmetrically arranged in spaced relationship so as to present interrupted and irregular parting lines between the surfaces.

Illustrative embodiments of the invention are shown in the accompanying drawing, in which:

Fig. 1 is a front elevational view, partly in section, of a lapping machine embodying the invention.

Fig. 2 is a fragmentary, horizontal, sectional view taken on the line 2—2 of Fig. 1.

Fig. 3 is a fragmentary, vertical, sectional view taken on the line 3—3 of Fig. 2.

Fig. 4 is a fragmentary, vertical, sectional view of a lapping machine embodying an additional form of the invention.

In the form of the invention illustrated in Figs. 1 to 3, inclusive, of the drawing, the improved lapping machine comprises a base structure, generally designated by the numeral 10, having a lower horizontal bed portion 11 and an upstanding vertical back portion 12. Formed in the bed portion 11 is a cylindrical bore 13 having counterbored recesses 14 at its opposite extremities. A tubular journal member 15 is rotatively supported in the cylindrical bore 13 by bearings 16 disposed in the recesses 14. Each bearing 16

comprises inner and outer bearing rings 17 and 18, respectively, between which is disposed a series of ball bearings 19. The tubular journal member 15 is provided at its upper end with a radial flange 20 which is seated upon the upper edge portion of the inner bearing ring 17, as illustrated in Fig. 1. Formed in the upper end portion of the journal member 15 is a counterbore 21 in which a bushing 22 is disposed. The lower end portion of the journal 15 is a suitable

counterbore, as illustrated at 23, for the reception of a roller bearing unit 24, which is removably held in the lower end portion of the journal member 15 by a threaded plug 25.

A combined work supporting and lapping element 26 having a spindle portion 27 journalled in the bushing 22 and bearing unit 24 is rotatably mounted in the journal member 15, the bushing 22 and bearing unit 24 being so constructed and arranged as to bring the rotative

axis of the spindle 27 into eccentric relationship with respect to the rotative axis of the journal member 15. This may be accomplished by suitable bushing and bearing construction or by forming the counterbores 21 and 23 of the journal member 15 eccentric with respect to the axis of rotation of the latter. The lower end portion of the spindle 27 is provided with a reduced end portion 28 on which a pulley 29 is non-rotatably fixed. A collar 30 having a belt groove 31 therein is non-rotatably fixed on the lower end portion of the journal member 15 which extends below the lower extremity of the bed portion 11 of the base structure. The pulley 29 and collar 30 are drivingly connected by belts 32 and 33 to driving pulleys 34 and 35 mounted on a shaft 38 of an electric motor 37, or other suitable driving means carried by the base structure 10. Belt tensioning members 38 and 39 having idler wheels 40 and 41 on their free end portions, respectively, are provided for taking up the slack in the belts 32 and 33. The combined lapping and work supporting element comprises a disc 42 mounted on the upper end portion of the spindle 27.

Vertically slidably mounted on the upstanding back portion 12 of the base structure 10 is a reciprocable carriage 43 having a tongue 43' projecting from its rearward side and slidably engaged in a corresponding groove 44 formed in the face of the back portion 12. Mounted on the lower end portion of the reciprocable carriage 43 is a block 45 having a cylindrical bore 46 therein and provided with counterbore recesses 47 at its upper and lower extremities. Mounted in the counterbore recesses 47 are roller bearing units 48 in which a tubular journal member 49 is rotatably mounted. The lower end portion of the tubular journal member 49 is counterbored and provided with a bushing 50 and the upper end portion of the tubular journal member 49 is similarly provided with a counterbore in which is mounted a roller bearing member 51.

A lapping tool, generally designated by the numeral 52, is rotatably mounted on the block 45 and has a spindle portion 53 journaled in the bushing 50 and roller bearing unit 51. Provided on the lower extremity of the spindle portion 53 is a disc 54 which is disposed in opposing relationship with respect to the disc 42 of the combined work support and lapping tool 26. The bushing 50 and bearing unit 51 are preferably so constructed and arranged as to bring the axis of rotation of the spindle 53 into eccentric relationship with respect to the axis of rotation of the journal member 49, as illustrated at 54' in Fig. 1. The upper end portion of the tubular journal member 49 and spindle 53 extend beyond the corresponding end portion of the block 45, and the spindle 53 has a reduced end portion 55 which extends beyond the upper end portion of the journal member 49. Non-rotatably secured to the reduced end portion 55 of the spindle 53 is a pulley 56. A collar 57 having a pulley groove 58 therein is non-rotatably keyed to the external end portion of the journal member 49. The pulleys 56 and collar 57 are drivingly connected by belts 59 and 60, with driving pulleys 61 and 62, respectively, mounted on a shaft 63 of a motor 64. The motor 64 is carried by an extension 65 of the carriage 43, as illustrated in Fig. 1. Provided on the back portion 12 of the base structure 10 is a forwardly pro-

truding lug 66 in which is threaded an adjustable set screw 67 that may be selectively fixed in a predetermined position by a lock nut 68. The head of the set screw 67 is adapted to register with a lug 69 formed integral on the carriage 43 in order to limit downward movement of the carriage and predetermine the spaced relationship between the discs 42 and 54 of the lapping tools 26 and 52, respectively.

The vertically reciprocable carriage 43 is counterbalanced, in order to facilitate convenient movement thereof to accommodate the placement of work between the lapping tools 26 and 52 by the provision of a cable 70 which is attached to the carriage 43 at 71 and extended over pulleys 72 and 73. The free end of the cable is provided with a support 74, upon which weights 75 may be placed. In practice, a sufficient number of weights 75 are placed on the support 74 to substantially accurately balance the mass of the carriage 43 and all parts of the apparatus supported thereby. After this is accomplished, a selected number of weights 76 may be mounted on the upper extremity of the carriage 43 in order to accurately predetermine the pressure with which the lapping tool 52 is applied to the work.

A single piece of work comprising a disc-shaped or other shaped structure (not shown) may be disposed between the lapping tool 26 and 52, on the adjacent sides of which are provided lapping elements 77 and 78, respectively, which will be hereinafter more clearly described. During operation of the opposed lapping tools by their respective motors 37 and 64, both sides of the work, which may be suitably held, if desired, against movement relative to the base structure 10 by any suitable clamping means, are simultaneously operated upon. The combined rotating and revolving actions of both of the lapping tools 26 and 52, which may be caused to occur in the same or in opposite directions depending upon the direction of drive of the motors 37 and 64, produces a movement of the lapping surfaces relative to the work which is a resultant of the component revolving and rotating movement resulting from the eccentric relationship of the axis of the spindle of the lapping tools with respect to the rotating journal members in which they are mounted. By virtue of this action, the repeated application of localized areas of lapping surface to the same increment of area of the surface of the work is effectively guarded against and the lapping surface is so moved with respect to the work surface as to efficiently remove even microscopic machine-formed grooves and ridges from the surface of the work without forming scratches thereon by repeated retracing of localized hard particles of the lapping surface over the same increment of the area of the work.

In the form of the invention illustrated in Figs. 1 to 3, inclusive, the lapping machine is equipped with apparatus for accommodating simultaneous lapping of the cylindrical parts of a plurality of articles, such as the stems of valves of the type commonly used in internal combustion engines. The valves 79 are preferably disposed in a radial arrangement, as illustrated in Fig. 2, with their stem portions interposed between the lapping elements 77 and 78 of the lapping tools 26 and 52, respectively. A spider 80 comprising a disc having radial slots 81 therein for accommodating the valve stems, is preferably located between the lapping elements 77 and 78 and anchored against movement relative to the base structure 10 by

pins 82 mounted on the latter and received in apertures 84 of ears 85 formed integral with the spider 80. By disposing the stem portions of the valves 79 in the slots 81, the valves are held against displacement with respect to each other during the lapping operation while they are free to rotate about their longitudinal axes. Radially outward movement of the valves from between the lapping elements 77 and 78 is prevented by a track structure 86 mounted on the bed 11 and provided with spaced flanges 87 and 88 between which the head portions of the valves are received.

During simultaneous lapping of a plurality of articles in the foregoing manner, the direction of drive of the motors 37 and 64 is preferably predetermined to cause the lapping elements 77 and 78 to rotate in respectively opposite directions in order to promote rotation of the valves relative to their longitudinal axes, thereby introducing a further component of relative movement between the work and the lapping element.

The lapping elements 77 and 78 may comprise integral ring-shaped stones of either artificial compositions or natural stone which may be secured in a conventional manner to the disc portions 42 and 54, respectively, of the lapping tools. The lapping element illustrated comprises a plurality of differently shaped pieces of lapping material 89 which are rigidly bonded to a layer of rubber 90 provided on the side face of the disc portion 42 of the tool. The rubber layer 90 may be of a hard ebonite-like composition or it may be relatively soft and yieldable in order to provide a yieldable backing for the pieces of lapping material 89. By virtue of this construction, a multiplicity of discontinuous and irregular parting lines are provided between the particles of lapping material so that at no instance is a substantial portion of the length of the stems of the valves subjected to the action of a continuous edge portion of a particle of lapping material. Relative spacing of the particles of lapping material from each other, illustrated in Fig. 2, provides space accommodations for the fine powder-like substance which accumulates on lapping members and which comprises a combination of particles of the work and particles of the lapping material.

During operation of the foregoing lapping machine, either the lapping tool 26 or the lapping tool 52 may be allowed to remain at rest while the other lapping tool is rotated and revolved in the foregoing manner. If desired, one of the lapping tools may be subjected to a combined rotating and revolving action while the other is only revolved, or only rotated. This may be accomplished by employing all the driving belts 32, 33, 59 and 60 or by removing selected belts, as desired.

In Fig. 4 of the drawing is illustrated a lapping machine similar to that shown in Fig. 1 which includes opposed, rotatable and revolvable lapping members that are laterally, bodily offset a distance substantially equal to the radius thereof. Although the driving mechanism for the lapping members of the form of the invention shown in Fig. 4 is not included in this fragmentary figure, it is apparent that the structure of this form is so similar to that shown in Fig. 1 that the same driving apparatus may be employed to rotate and revolve the lapping members in any of the manners described in the discussion of the structures of the other figures. Corresponding parts of the structure shown in Figs. 1 and 4 are designated by identical numerals.

Disposed between the offset lapping tools 52 and 26, of the lapping machine shown in Fig. 4, is a work spacing and conveying spider 150, similar to the spider 80 of Fig. 1, having substantially radially extending work receiving slots 151 therein. The spider 150 is rotatably supported by a stem portion 152 secured to, or formed integral with its central portion, which is journaled in a support 153. The axis of the stem portion 152 may be concentric with the center of the lapping tool disc 42 or otherwise so suitably spaced therefrom as to bring a substantial portion of the spider between the opposed portions of the lapping elements 77 and 78 of the lapping tools. The slots 151 of those portions of the spider which do not extend between the lapping surfaces 77 and 78 may be progressively loaded with pieces of work, illustrated at 154, and the spider may be progressively turned either manually, mechanically or automatically by driving mechanism (not shown) in either a continuous or intermittent manner. Lapped work can be removed as it is carried outwardly by the spider from between the lapping elements 77 and 78 and the spider may be refilled progressively with work to be lapped.

Although but several specific embodiments of the invention are herein shown and described, it will be understood that various changes in the size, shape and arrangement of parts may be made without departing from the spirit of my invention.

What I claim is:

1. Lapping apparatus comprising a base structure, a carriage rotatably mounted on said base structure, means for supporting work including a work table rotatably mounted on said carriage in eccentric relationship with respect to the axis of said carriage and including a member for holding articles supported thereon against translatory movement with respect to said base structure, a lapping element on the work supporting face of said work table, means for simultaneously drivingly rotating said work table about the rotative axis thereof and revolving the same about the axis of said carriage, a lapping tool carrier rotatably mounted on said base structure, a lapping tool rotatably mounted on said tool carrier in eccentric relationship with respect to the axis of the latter and having a lapping element thereon disposed in opposing relationship with respect to the lapping element of said work table, and means for simultaneously drivingly rotating said tool about its rotative axis and revolving the same about the axis of said tool carrier.

2. Apparatus for finishing peripheral surfaces of work having portions of circular cross section comprising a base structure, a carriage rotatably mounted on said base structure, means for supporting work including a work table rotatably mounted on said carriage in eccentric relationship with respect to the axis of said carriage, an abrading element on the work supporting face of said work table, means for simultaneously drivingly rotating said work table about the rotative axis thereof and revolving the same about the axis of said carriage, a finishing tool having an abrading element thereon disposed in opposing relationship with respect to said work table and adapted to operate upon peripheral surfaces of work disposed between it and said abrading element of said work table, and a member disposed between said abrading elements for holding pieces of work against translatory movement with respect to said base structure while accommodating rolling of said peripheral surfaces between said abrading elements.

3. Lapping apparatus comprising a base structure, means mounted on said base structure for supporting work including a work table having a lapping element thereon and a member for holding the periphery of a piece of work in rotative contact with said element and against translatory movement relative to said base structure, a lapping tool carrier rotatably mounted on said base structure, a lapping tool rotatably mounted on said tool carrier in eccentric relationship with respect to the axis of the latter and having a lapping element thereon disposed in opposing relationship with respect to the lapping element of said work table, and means for simultaneously drivingly rotating said tool about its rotative axis and revolving the same about the axis of said tool carrier.

4. Lapping apparatus comprising a base structure, means rotatably mounted on said base structure for supporting work including a rotatable work table having a lapping element thereon and a member for holding the periphery of a piece of work in rotative contact with said element and against translatory movement relative to said base structure, said member being adapted to accommodate rotation of said work about one of its axes, means for drivingly rotating said work table, a lapping tool carrier rotatably mounted on said base structure, a lapping tool rotatably mounted on said tool carrier in eccentric relationship with respect to the axis of the latter and having a lapping element thereon disposed in opposing relationship with respect to the lapping element of said work table, and means for simultaneously drivingly rotating said tool about its rotative axis and revolving the same about the axis of said tool carrier.

5. Apparatus for lapping peripheral portions of pieces of work comprising a base structure, means rotatably mounted on said base structure for supporting work including a rotatable work table, a lapping element on the work supporting face of said work table, means for drivingly rotating said work table, a lapping tool carrier rotatably mounted on said base structure, a lapping tool rotatably mounted on said tool carrier in eccentric relationship with respect to the axis of the latter and having a lapping element thereon disposed in opposing relationship with respect to the lapping element of said work table, means for simultaneously drivingly rotating said tool about its rotative axis and revolving the same about the axis of said tool carrier, and a member for holding said peripheral portions of said work against translatory movement relative to said lapping elements while accommodating rotative movement thereof.

6. Lapping apparatus comprising a base structure, a journal member rotatably mounted on said base structure, a support shiftably mounted on said base structure for reciprocatory movement toward and away from said journal member, a second journal member rotatably mounted on said shiftable support, a spindle rotatably

mounted in each journal having a rotative axis eccentric with respect to the latter, lapping elements on said spindles in opposed facing relationship with respect to each other, means for independently rotating said journals with respect to their rotative axes and said spindles with respect to their rotative axes respectively, and a member interposed between said lapping elements normally spaced therefrom for holding peripheral portions of pieces of work in rotative contact with said lapping elements and against movement in unison therewith.

7. Lapping apparatus comprising a base structure, a journal member rotatably mounted on said base structure, a support shiftably mounted on said base structure for reciprocatory movement toward and away from said journal member, a second journal member rotatably mounted on said shiftable support, a spindle rotatably mounted in each journal having a rotative axis eccentric with respect to the latter, lapping elements on said spindles in opposed facing relationship with respect to each other, means for drivingly rotating said spindles and the lapping elements thereon in respectively opposite directions about their axes, means for drivingly rotating said journals about their axes, and a spider disposed between said lapping elements having a plurality of slots therein for holding a plurality of pieces of work in rolling lapping engagement with said lapping elements.

8. Lapping apparatus comprising a base structure, a journal member rotatably mounted on said base structure, a support shiftably mounted on said base structure for reciprocatory movement toward and away from said journal member, a second journal member rotatably mounted on said shiftable support, a spindle rotatably mounted in each journal having a rotative axis eccentric with respect to the latter, lapping elements on said spindles in opposed facing relationship with respect to each other, means for independently rotating said journals with respect to their rotative axes and said spindles with respect to their rotative axes respectively, means for holding a plurality of pieces of work in a spaced arrangement between said lapping elements, and apparatus for predeterminedly determining the force of application of said lapping elements to said work.

9. In a lapping machine having a base, opposed rotatable lapping elements and a work cage therebetween, a pair of rotatable spindles to support said elements, means simultaneously and positively to rotate said spindles in opposite directions, a pair of aligned rotatable sleeves rotably supported in said base, eccentric bearing supports in said sleeves for said spindles, and driving means simultaneously and positively to rotate said sleeves to impart a planetary movement to each of said spindles and elements simultaneously and uniformly to lap the opposite faces of a plurality of work pieces.

DAVID A. WALLACE.
